US00D822685S

(12) **United States Design Patent** (10) **Patent No.:** **US D822,685 S**
(45) **Date of Patent:** **** Jul. 10, 2018**

(54) **DISPLAY SCREEN OR PORTION THEREOF WITH GRAPHICAL USER INTERFACE**

(71) Applicant: **Intuitive Surgical Operations, Inc.**, Sunnyvale, CA (US)

(72) Inventors: **Lauren L. Argo**, San Francisco, CA (US); **Federico Barbagli**, San Francisco, CA (US); **Ruchi C. Bhatt**, San Jose, CA (US); **Christopher R. Carlson**, Belmont, CA (US); **Energy Cruse, II**, Foster City, CA (US); **Vincent Duindam**, San Francisco, CA (US); **Scott S. Ichikawa**, Seattle, WA (US); **Aaron B. Tinling**, Chimacum, WA (US); **Oliver J. Wagner**, Mountain View, CA (US)

(73) Assignee: **INTUITIVE SURGICAL OPERATIONS, INC.**, Sunnyvale, CA (US)

(**) Term: **15 Years**

(21) Appl. No.: **29/600,991**

(22) Filed: **Apr. 18, 2017**

(51) LOC (11) Cl. **14-04**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design; and,

FIG. 2 is a front view of a second embodiment of the display screen or portion thereof with graphical user interface showing our new design.

The long-dash/short-dash/short-dash broken line illustrates the display screen and the boundary of the claimed design and forms no part thereof.

1 Claim, 1 Drawing Sheet
